ROLL STOPPAGE MEANS FOR WRINGERS

Donald F. Fairgrieve, Toronto, Ontario, Canada, assignor to Fairgrieve & Son, Limited, Toronto, Ontario, Canada

Application March 21, 1955, Serial No. 495,478

8 Claims. (Cl. 68—253)

This invention relates to improvements in washing machines of the pressure roll wringer type, and more particularly to a safety mechanism for controlling the drive to the wringer rolls.

The wringer of a conventional washing machine has long been recognized as a serious hazard to the operator unless great care is taken, the fingers and hands are likely to be pulled into the nip of the pressure rolls and many forms of wringer releases have been devised whereby the top bar can be released to relieve the pressure on the rolls.

Another serious source of hazard is the fact that parts of the operator's clothing, such as a sash, full sleeve, tie or the like, may also be fed between the rolls and in the event that such clothing becomes wound on one of the rolls, the release of the roll pressure has no effect and the material continues to be wound on the roll as the roll rotates endangering the operator or tearing the clothing unless the operator has the presence of mind or is in a position to immediately stop the roll drive.

It is the object of this invention to enable roll drive or feed to be automatically stopped as an incident of effecting roll pressure release.

Many roll pressure releases are effected through what is commonly referred to as instinctive mechanisms wherein the involuntary movement of the operator whose fingers, clothing, etc. are caught or nipped in the rolls effects top bar and hence roll pressure release. Other roll pressure releases are effected through release handles, release bars, etc., which may be operated in one or more directions to effect roll pressure release.

It is another important object of the invention to enable the roll drive to be automatically stopped on pressure release regardless of what type of top bar pressure release mechanism is employed.

Still another important object is to enable roll drive stoppage to be simply and inexpensively effected as aforesaid without requiring any modification or change of the conventional drive mechanism.

Again it is an object to provide a safety mechanism as aforesaid which will be concealed within the top bar.

The principal feature of the invention resides in providing a declutching mechanism which is rendered inoperative on setting of the top bar in the locked or roll pressure applying position and which on release of the top bar is rendered operative to actuate the roll drive clutch mechanism to stop roll drive regardless of the direction of roll rotation. More particularly according to the invention the declutching mechanism acts to engage the roll drive clutch lever to return it to or hold it in the neutral position so that the wringer rolls cannot be driven until the mechanism is rendered inoperative by the setting of the top bar in roll pressure applying position at which time the clutch arm may be operated in the conventional manner to drive the rolls in either direction.

Another important feature resides in mounting the safety or declutching mechanism within the top bar which conventionally is of channel shape so that it is concealed.

2

More particularly according to the preferred form of the invention the clutch lever is mounted to swing on a vertical pivot from a central position substantially in alignment with the top bar to roll drive coupling positions either side of the central position, and the actuating safety mechanism comprises a spring actuated member swingable or movable in a direction longitudinally of the top bar, the spring actuated member and lever being provided with interengaging surfaces symmetrically disposed on opposite sides of the lever pivot to effect movement of the lever to, and hold it at the central position irrespective as to which side of the central position the lever was actuated, the spring actuated member being actuated by the top bar when the latter is moved to the roll pressure applying position to clear its lever engaging surfaces from lever-engagement.

These and other objects and features will be understood from the following detailed description taken in conjunction with the accompanying drawings, in which:

20 Figure 1 is a fragmentary plan view of the upper end of a gear case of a wringer to which a roll stopping safety mechanism in accordance with the invention has been applied, the top bar of the wringer being omitted.

Figure 2 is a part side elevational view part vertical sectional view showing the roll stopping mechanism of Figure 1 rendered inoperative by the top bar.

Figure 3 is a view similar to Figure 1 but showing the roll stopping device operated to swing the clutch member to the neutral position.

30 Figure 4 is a view similar to Figure 2 but showing the top bar raised and the roll stopping device actuated to roll stopping position.

Figure 5 is a perspective view, partly broken away, of a wringer having the roll stoppage device of Figures 1 to 4 applied thereto.

Figure 6 is an enlarged fragmentary perspective view showing the relation between the moving member of the roll stopping device and the clutch lever.

Figure 7 is a plan view of the clutch lever and driving gears.

With reference first to Figure 5 the wringer illustrated comprises the usual side stiles 1 and 2 carrying vertical channel guides 3 in which are mounted wringer or pressure rolls 4 which may be journaled in suitable blocks 5 slidably mounted in the channels 3. Applying pressure to the rolls 4 is the usual spring 6 seated on the blocks 5 and adjusted by a screw 7 operating through the top of a channel shaped top bar 8.

The top bar 8 is pivotally connected at one end to a channel shaped bracket 9 mounted on top of a gear case 10 to which the side stile 1 is connected.

Securing the opposite end of the top bar to the side stile 2 is a toggle mechanism such as fully described in my United States Patent No. 2,726,530 dated December 13, 1955, which permits the top bar to be drawn down to a pressure-applying or set position and when released, permits the top bar to swing upwardly, releasing pressure on the rolls. This toggle comprises a lever 11 pivoted to the end of the top bar, and a link 12 pivoted to the side stile at 13 and to the lever intermediately of its length by means of a pivot pin 14. Mounted on the side stile 2 is a latch hook 15 which is adapted to engage the pivot pin 14 of the toggle mechanism when the toggle mechanism is actuated to bring the top bar to the "set" position to maintain the toggle mechanism and top bar in the set position.

A pivotal channel member 16 disposed normally horizontally across the outside of the side stile 2 and pivotally supported about a centre pivot 17 is adapted to be actuated by the cranked ends 18 of one or more pivotal top bar release bars 19 engaging in slots 20 in the ends

of the channel member. The swinging of the release bars 19 in either an upward or a downward direction actuates the channel member 16 to depress the latch hook 15 against the action of a spring 21 to effect release of the toggle mechanism and release of the top bar.

It will be understood that the top bar, toggle mechanism and release mechanism above described are simply representative of one type of mechanism for accomplishing the top bar release by way of illustrating the application of the invention, and other types of top bar release and locking mechanisms may be employed as desired.

The drive for the rolls 4 is achieved from the drive shaft 22 driving a pinion 23 which engages a pair of gears 24 loosely mounted on a roll drive shaft 25 on which is splined a clutch mechanism 26 provided with clutch teeth 27 to engage in suitable slots or recesses 28 in the gears 24 as in conventional practice. The gears 24 are driven one in one direction, and one in the other direction, and the sliding of the clutch mechanism 26 to engage the clutch teeth 27 with the recesses or slots 28 of one of the gears effects drive of the roll drive shaft 25 in one direction while engagement of the clutch mechanism with the opposite gear effects drive of the roll drive shaft in the opposite direction.

The gears 24 and clutch mechanism 26 are housed within the gear case 10 and the clutch mechanism is actuated by a lever 29 pivoted about a vertical axis on a pin projection 30 projecting through the top of the gear case 10 and carrying an eccentric pin extension 31 operating in a bore of a square cam 32 fitted into an annular groove 33 formed in the periphery of the clutch mechanism 26. The disposition of the cam 32, eccentric pin 31 and pin 30 are such that with the lever 29 extending in a direction substantially in alignment with the top bar 8 the clutch mechanism 26 is disposed in a neutral position as illustrated in Figure 5 uncoupling the roll drive shaft 25 from engagement with either of the gears 24.

The lever 29 is located below the bracket 9 which is cut away towards the outside of the gear case to allow horizontal pivotal movement of the lever either side of the aligned neutral position of Figures 3 and 5.

The lever 29 as best seen in Figure 6 is in the form of a flat bar having a reduced end 34 which is threaded to receive a knob 35 forming the lever handle. The opposite end of the lever is turned upwardly to provide a curved upturned flange 36 which is symmetrical about the pivot pin 30 and presents stop or cam surfaces 37 disposed symmetrically on opposite sides of the pin 30 to form a means of returning the lever 29 to the central or neutral position as hereinafter more fully explained.

Pivotedly secured between the spaced walls 38 of the channel bracket 9 substantially immediately above the pivot pin 30 is a channel member 39 which swings on a horizontal axis extending transversely of the top bar 8. The channel member 39 is urged in a clockwise direction by a spring 40 secured to the member and to a cross bar 41 carried by the bracket 9. The channel member 39 straddles the lever 29 extending equidistant on opposite sides of the pivot pin 30. With the lever 29 in the central neutral position, the member 39 is adapted to engage both surfaces 37 to locate the lever and maintain it in its neutral position. In the event that the lever 29 is operated to either side of its central neutral position to effect roll drive through the clutch mechanism 26, the member 39 on swing under action of the spring 40 will engage one of the edges or surfaces 37 only at one side of the pivot pin 30 to rotate the lever back to the central or neutral position, whereupon it will then contact the other surface 37, effectively stopping the lever in the central position.

A further triangular channel member 42 is pivotally supported at the uppermost point of the bracket 9 at one apex and has its lower apex connected to the channel

member 39 by means of pivotal push arms 43, while located on the upper surface of the member 42 adjacent its upper apex is an upwardly projecting adjustable screw 44, which is adapted to engage the top of the channel shaped top bar 8.

With the top bar in the released position as illustrated in Figures 4 and 5, the spring 40 acts to move the channel member 39 on its pivot so that the lower end of the member is swept longitudinally of the top bar to the limit position, and the triangular member 42 is actuated by the push arms 43 to swing its upper apex and the screw 44 mounted adjacent thereto, upwardly.

Upon setting of the top bar in the roll pressure applying position, as illustrated in Figure 2, the top bar through engagement with the screw 44, depresses the channel member 42, and through the push arms 43 swings the channel member 39 in a counterclockwise direction about its pivot against the action of the spring 40 to clear the channel member from the cam or stop surfaces 37 of the lever 29, allowing the lever to be swung to either side of its central position, depending on which direction of roll drive is desired. Thus with the top bar set in the pressure applying position, the clutch lever 29 may be operated in the conventional manner to start and stop the rolls with the clutch mechanism functioning in the conventional manner. However, the instant that the top bar 8 is released by the release bars 19 or any other suitable mechanism provided, the pressure on the triangular channel member 42 is removed, and the spring 40 functions to swing the channel member 39 in the clockwise direction, swinging the lever 29 to the central neutral position irrespective of the position which it formerly occupied immediately prior to top bar release to effect roll drive stoppage.

It will thus be seen that roll drive stoppage is automatically effected by the top bar release without any further movement on the part of the operator, and any clothing, etc. caught in the rolls will automatically be prevented from winding on the rolls by the simple expediency of releasing the top bar. However, when the top bar is in the set position, the mechanism effecting roll stoppage is rendered inoperative, and the clutch for controlling the roll drive can be actuated in the conventional manner.

While the stop surfaces 37 of the lever 29 are shown as comprising the end edges of the upturned lever flange 36, it will be appreciated that any symmetrical disposition of projections on the lever may be provided.

By arranging the roll stoppage mechanism to lie within the channel of the top bar it is conveniently hidden from view and in no way increases the size or bulkiness of the wringer.

It will also be understood that various other changes in the details and arrangements of parts which have been herein described and illustrated in order to explain the nature of the invention may be made by those skilled in the art within the principle and scope of the invention, as set forth in the appended claims.

What I claim as my invention is:

1. In a wringer having side stiles, wringer rolls mounted in said side stiles, a reversing drive for said rolls including a clutch mechanism for coupling said rolls to said drive, an inverted channel shaped top bar bridging said stiles and movable from a position applying pressure on said rolls through a stiff spring member to a position releasing said rolls from pressure, means for retaining said top bar in pressure applying position, and means for releasing said top bar from said pressure applying position, said clutch mechanism including a lever pivotally supported on a vertical pivot beneath said top bar adjacent one end thereof to swing from a central neutral position substantially in alignment with said top bar to a position on each side of said central position to couple said rolls to said drive on one side of said central position for one direction of rotation, and on the other side of said central position for the opposite direction of rotation, said lever

being formed with upwardly projecting surfaces symmetrically disposed on opposite sides of said pivot, means disposed beneath said top bar to move longitudinally thereof and engage one or the other of said projecting surfaces with said lever swung away from said central neutral position and to swing said lever to said central position, whereupon both said surfaces are engaged to locate said lever in said neutral position, spring means acting on said lever surface engaging means to actuate said lever to said central position, and means actuated by said top bar when said top bar is in said roll pressure applying position to displace said lever surface engaging means out of engagement with said lever surfaces.

2. A device as claimed in claim 1 in which a support frame is disposed within the channel of said top bar and said lever surface engaging means comprises a channel member pivotally supported on said frame on a horizontal pivot extending transversely of said top bar and disposed approximately immediately above the pivot of said lever, said channel member extending substantially symmetrically on opposite sides of said lever pivot.

3. A device as claimed in claim 2 in which said means actuated by said top bar comprises a control member pivoted to said frame, link means connecting said latter member to said pivotal channel member, said control member being disposed to swing under action of said spring means acting on said channel member to a position projecting above said frame into the path of said top bar when the latter is moved to said roll pressure applying position thereupon to be actuated by said top bar to displace said channel member clear of said lever surface projections.

4. A device as claimed in claim 3 in which said control member is provided with an adjustable upward projecting member engageable with said top bar.

5. In a wringer having side stiles, rolls mounted in said side stiles, a drive for said rolls including oppositely rotating drive members, a clutch mechanism interposed between said drive and said rolls and operable from a neutral position in which said drive is uncoupled from said rolls to positions coupling said rolls to one or other of said oppositely rotating drive members, a lever for actuating said clutch mechanism comprising a horizontal member pivotally supported to swing about a vertical axis at the upper end of one of said side stiles either side of a central position comprising said neutral position to effect drive of said rolls in opposite directions, said lever having upwardly projecting surfaces disposed symmetrically on opposite sides of said axis, a releasable top bar for applying pressure to said rolls, means for releasing said top bar from pressure applying position, and means responsive to the release of said top bar to actuate said lever to move said clutch mechanism to said neutral position, said latter means comprising a pivotal spring

biased member movable above said lever and in a direction substantially perpendicular to said lever axis to engage one or other of said projecting surfaces with said lever swung to one side of said neutral position to return said lever to said neutral position, and lever means adapted to be directly engaged by the underside of and actuated by said top bar to clear said pivotal spring biased member from engagement with said surfaces with said top bar moved to said roll pressure applying position.

10 6. In a wringer having side stiles, rolls mounted in said side stiles, a drive for said rolls including oppositely rotating drive members, a clutch mechanism interposed between said drive and said rolls and operable from a neutral position in which said drive is uncoupled from said rolls to positions coupling said rolls to one or other of said oppositely rotating drive members, a lever for actuating said clutch mechanism comprising a horizontal member pivotally supported to swing about a vertical axis at the upper end of one of said side stiles to either

15 side of a central position comprising said neutral position to effect drive of said rolls in opposite directions, said lever having upwardly projecting surfaces disposed symmetrically on opposite sides of said axis, a releasable top bar for applying pressure to said rolls, means for releasing said top bar from pressure applying position, and means responsive to the release of said top bar to actuate said lever to move said clutch mechanism to said neutral position, said latter means comprising a spring

20 biased member movable above said lever and substantially perpendicular to said lever axis to engage one or other of said projecting surfaces with said lever swung to one side of said neutral position to return said lever to said neutral position, and lever means adapted to be

25 actuated by movement of said top bar to said roll pressure applying position to clear said spring biased member from engagement with said surfaces.

26 7. A device as claimed in claim 6 in which said last mentioned lever means carries an adjustable member projecting therefrom and adjustable towards and from said top bar to adjust lever movement on closure of the top bar.

27 8. A device as claimed in claim 7 in which said adjustable member comprises an adjusting screw adjustable towards and from said top bar and means for locking said

28 40 adjusting screw in adjusted position.

29 45 30 35 36 37 38 39 40 41 42 43 44 45 46 47 48 49 50
